UNITED STATES PATENT OFFICE.

FRITZ R. JOHNSON, OF PROVIDENCE, RHODE ISLAND.

COMPACT CONTAINER.

Application filed March 28, 1924. Serial No. 702,516.

To all whom it may concern:

Be it known that I, FRITZ R. JOHNSON, a citizen of the United States, residing at Providence, in the county of Providence and State of Rhode Island, have invented certain new and useful Improvements in Compact Containers, of which the following is a specification.

My invention relates to holders for cosmetics commonly known as vanity boxes or compact containers.

An essential object of my invention is to enable the mirror, when the parts are open for use, to be moved not only upwardly, and downwardly, but also edgewise whereby reflection is afforded from a variety of lateral angles. Another object is certainty and facility of operation.

My invention consists in the means for producing the above results substantially as hereinafter claimed.

In the accompanying drawings forming a part of this invention

Figure 1 is a perspective view of my novel device,

Figure 2, a section on line 2—2 of Figure 1,

Figure 3, a longitudinal central section of the same with the parts in open position,

Figure 4, a fragmentary plan view of the same, and

Figure 5, a detail view of the slidable member.

Like reference characters indicate like parts throughout the views.

For the purpose of illustrating my invention I have shown in the drawings a box or case consisting of a hollow body section 40 consisting of a bottom 9 and side 10 and adapted to hold powder and a puff. Also a cover section 12 comprising a top 13 and a side 14. In the construction illustrated a hinge 17 connects the two sections. A horizontal plate 20 is fixed in any convenient manner in an intermediate portion of the cover. In this instance the plate 20 has a peripheral flange 21 held frictionally or by solder to the side 14. A central depression 22 in the plate affords a seat for a disk of rouge or other cosmetic and a puff; and a curved slot 24, forming the arc of a circle concentric with the center of the plate, is located in the margin of the latter. A rivet or other pivot member 26 in the center of the plate engages one end of a flat oscil-

latory member 28 slidably engaging that face of the plate which is adjacent the top 13 of the cover. The free end of the member 28 is provided with a portion 29 bent 60 at an angle to the member and extending loosely through the slot 24.

A mirror member 32 is hinged to the portion 29. This comprises a backing plate 34 provide with a retaining flange 35 65 engaging a mirror glass 36. A peripherally projecting portion 38 of the plate 34 has hinge sleeves 39 embracing a pintle 40 which in turn is embraced by a hinge sleeve 41 upon the end of the bent portion 29 of the member 28, thus forming a hinge represented generally by 42.

A projection 45 on the body section is adapted to snap into a cavity 46 in the cover section. A lug 47 on the mirror member is adapted to snap into a catch 48 on the plate 20.

In closed position, as shown in Figure 2, the mirror member 32 is folded and retained in the cover section 12 against the plate 20 and encloses the space 50 for the cosmetic and puff. The mirror member overhangs the space 51 in the body section for the powder and powder puff.

In open position it will be noted, by reference to Figures 3 and 4, that the mirror member is not only capable of elevation, but also that the slot 24 permits the arm 28 to slide laterally and thus permit the mirror member to assume any transverse or lateral angle relatively to the operator who is supporting the sections 8 and 12 in open position.

I do not desire to be understood as confining myself to the specific construction and relative arrangement of parts shown, as such changes and modifications may be made in practice as fairly fall within the scope of my invention as claimed.

What is claimed is:

1. In a compact container, two hollow sections, a laterally slidable member supported in one section, and a mirror member hinged to the slidable member.
2. In a compact container, two hollow sections, a plate in one section, a mirror member, and a slidable member retained by the plate pivotally supporting the mirror member.
3. In a compact container, two hollow sections, a plate in one section provided with a slot, a member pivotally attached to the

plate and projecting loosely through the slot, and a mirror member hingedly connected to the projecting portion of the pivoted member.

5. In a compact container, two hollow sections, a horizontal plate provided with a central depressed portion and with a

curved marginal slot, an oscillatory member slidably supported by the plate in the slot, and a mirror member carried by the oscillatory member. ¹⁰

In testimony whereof I have affixed my signature.

FRITZ R. JOHNSON.
